(57) **CLAIM**

The ornamental design for a vehicle headlight with illuminable light sequence, as shown and described.

DESCRIPTION

FIG. 1 is a front view of a vehicle headlight in a first state in a sequence of a front view of a vehicle with illuminable light sequence showing our new design; FIG. 2 is an enlarged view of the called out portion of FIG. 1;

FIG. 3 is a second state thereof;

FIG. 4 is an enlarged view of the called out portion of FIG. 3;

FIG. 5 is a third state thereof;

FIG. 6 is an enlarged view of the called out portion of FIG. 5;

FIG. 7 is a fourth state thereof;

FIG. 8 is an enlarged view of the called out portion of FIG. 7;

FIG. 9 is a fifth state thereof; and,

FIG. 10 is an enlarged view of the called out portion of FIG. 9.

The appearance of the transitional image sequentially transitions between the images shown in FIGS. 1, 3, 5, 7 and 9. The process or period in which one image transitions to another image forms no part of the claimed design.

The broken lines illustrate portions of the vehicle headlight with illuminable light sequence that represent a boundary and form no part of the claimed design, with the rest of the vehicle shown in de-emphasized, reduced tonal value so as to illustrate environmental structure. The elements shown outside the broken lines form no part of the claimed design and are merely included to show environmental aspects thereof.

1 Claim, 10 Drawing Sheets
